TWO-STAGE ISOMERIZATION OF N-HEPTANE

Filed Jan. 22, 1946

UNITED STATES PATENT OFFICE

2,583,740

TWO-STAGE ISOMERIZATION OF
N-HEPTANEJacob D. Kemp, San Francisco, Calif., assignor
to California Research Corporation, San Fran-
cisco, Calif., a corporation of Delaware

Application January 22, 1946, Serial No. 642,605

2 Claims. (Cl. 260—683.5)

1

The present invention relates to the isomerization of normal paraffins to highly branched paraffins and pertains more particularly to the isomerization of normal paraffins of six to nine and especially seven to eight carbon atoms to isoparaffins having at least two side chains.

Heretofore, many proposals have been made for isomerizing normal paraffins, particularly lower paraffins, such as normal butane, to isoparaffins having one side chain, such as isobutane. It has often been incidentally mentioned to further isomerize isoparaffins to more highly branched compounds. However, such proposals are found to be unsatisfactory and have failed to go into commercial production for many reasons. Among others, the disadvantages include too much side reaction with the production of unwanted products, cracking, disproportionation, polymerization, reversion to the normal paraffins or to compounds having a lesser number of side chains, or low yields or conversion.

It is therefore an object of the present invention to provide an improved isomerization process for the production of high yields of highly branched paraffins without attendant disadvantageous high proportion of side reactions.

It is another object of the present invention to provide an improved low temperature process for isomerizing normal paraffins having six to nine and especially seven to eight carbon atoms to isoparaffins having at least two side chains and especially to isoparaffins having at least three side chains, wherein yields of commercial importance are obtained.

Further objects and advantages of the present invention reside in special combinations of method steps, conditions, and the like, as will be readily apparent from the following description of preferred embodiments taken in reference to the drawing, which is a schematic flow diagram of one preferred embodiment of the present invention.

According to the present invention, it has been found that normal paraffins above butane and particularly normal paraffins having six to nine or more carbon atoms may be converted to isoparaffins of at least two side chains, and especially with seven to nine carbon atom normal paraffins to triply branched isomers, by isomerizing in at least two stages having a specific relationship of different operating conditions and in the presence of different added materials and generally low temperatures.

Briefly, a normal paraffin is subjected in the first stage to thorough contact with an isomeriza-

2

tion catalyst of relatively low activity and short contact time in the presence of a low-boiling isoparaffin and preferably at a relatively high temperature (as compared to subsequent treatment) to obtain a major reaction to isomers of one side chain. In the subsequent second stage or stages the single-branched isomers, i. e., isomers having an intermediate number of side chains or a mixture predominating in said isomers as produced in the first stage, are isomerized in the presence of a normal paraffin with an isomerization catalyst of relatively higher activity, and preferably at a relatively lower temperature. While hereinafter the preferred temperatures for carrying out the separate isomerization steps are spoken of as high and low temperatures, this is meant only as relative to each other, since the present process is normally carried out at low temperatures, i. e. below approximately 150° F. or thereabouts. While the conditions of lower catalyst activity and higher temperature in the first stage and of higher catalyst activity and lower temperature in the second or subsequent stage represents the most advantageous and superior form of the present invention, it is also contemplated that these conditions may, as noted hereinbelow, be varied from the above in correlation with other factors, such as contact time, nature of hydrocarbons, the proportion of added materials, etc. Thus, in the broadest sense, the present invention resides in a selective stepwise isomerization process employing in the first stage a substantial excess of a low-boiling isoparaffin and in the subsequent isomerization treatment of the first stage product employing a substantial excess of a liquid normal paraffin, preferably low-boiling and notably liquid propane.

By means of this process higher yields of isoparaffins having at least two side chains than have heretofore been obtained are now possible. In the present improved isomerization process the amount of material lost to side reaction is greatly reduced so that the economical production of highly useful hydrocarbons with several side chains can now be obtained. Thus, the present invention provides a selective stepwise isomerization process. The present invention is particularly important and highly advantageous for the economical production of triptane (2,2,3-trimethylbutane) from n-heptane by isomerization.

Suitable starting materials for the present process include normal paraffins, such as normal hexane, normal heptane, normal octane, normal

nonane. Concentrates containing 75% to 90% or more of a particular normal paraffin may be used. Petroleum fractions of relatively narrow boiling ranges, such as a heptane fraction, are especially suitable. Other fractions of non-petroleum origin, such as from Fischer-Tropsch synthesis, or the like, may be used. Substantially pure (i. e., above 90%) normal paraffins are preferred. The present process is particularly and most advantageously applied to relatively pure normal heptane and normal octane. For most convenient operation, the hydrocarbon feed material is freed of water, sulfur compounds, nitrogen bases, and other agents having deleterious action on the catalyst or imposing difficulties in catalyst regeneration.

Suitable low-boiling isoparaffins for use in the first isomerization stage include isobutane, isopentane, or sometimes isohexanes, or mixtures thereof. Especially preferred is isobutane or mixtures of isobutane and isopentane. The ratio of isoparaffin to normal paraffin to be isomerized is generally 0.5-5.0 to 1 by volume, usually greater than 1:1, and most effectively from 2-4 to 1. These isoparaffins are almost entirely unaffected in the isomerization zone, but permit a greater selectivity of isomerization toward the main desired product, i. e., from normal heptane to methylhexanes. In some cases, although normally less desirable, mixtures of these isoparaffins with low-boiling normal paraffins, such as propane, normal butane, normal pentane, etc., may be advantageously used, whereby a simultaneous isomerization of the low-boiling normal paraffins above propane and the higher boiling normal paraffins, e. g., heptane, takes place. These low-boiling iso- and n-paraffins may be obtained from extraneous sources, but preferably are mainly a part of the recycle stream of the small amount of side reaction products, which may also include some isobutane and isopentane.

In the second isomerization stage, the added n-paraffin is preferably a low-boiling n-paraffin of at least two carbon atoms, such as ethane, propane, normal butane, or normal pentane, or mixtures thereof. Propane is especially preferred and is found ideally suited for the isomerization of isoheptanes, mainly methylhexanes, to triptane. Higher n-paraffins may likewise be employed; thus, when the original starting material is normal heptane, the methylhexane fraction may be isomerized in the second stage in the presence of normal heptane. These normal paraffins are usually employed in excess over the isoheptanes. The ratio of these normal paraffins to isoparaffins charged is generally 2-20 to 1 and preferably 6-12 to 1 by volume.

In some cases, it is advisable to include a small or even substantial proportion of naphthenes, such as cyclopentanes, cyclohexanes, etc. or hydrogen (suitably at superatmospheric pressure) to the material charged to the isomerization stages.

Generally, any isomerization catalyst or mixture of catalytic agents, may be used, wherein the catalytic activity between the first and subsequent stages can be varied. The present process usually employs catalysts comprising metal halides of the Friedel-Crafts type and hydrogen halides. Suitable metal halides include particularly the chlorides and bromides of aluminum, and the halides of boron, zinc, iron, etc., which may be admixed with hydrogen chloride, hydrogen bromide or hydrogen fluoride. Also suitable are other catalyst modifiers or pro-

moters, such as water, lower alkyl halides, e. g., ethyl chloride or butyl chloride, lower aliphatic alcohols, e. g., butyl alcohol, etc., secondary promoters, or admixtures of the above and the like. Likewise, complexes formed by the combination of aluminum chloride or bromide with hydrocarbons, e. g., aluminum chloride-hydrocarbon complex from the reaction of aluminum chloride with butane during $AlCl_3$ isomerization of butane, may be employed, with or without additional promoters such as HCl or HBr. Aluminum halides may also be used with other metal halides such as halides of antimony, arsenic, zirconium, etc., or in liquid mixtures with other miscible compounds, such as nitrobenzene, ethyl ether, SO_2 , etc. Under some conditions, it may be advantageous for controlling catalyst activity and for depressing side reactions to provide for the presence of hydrogen. Particularly effective catalysts whose activity may be maintained at different levels are mixtures of HF and BF_3 , $AlCl_3$ and HCl, $AlBr_3$ and HBr, $AlCl_3$ -hydrocarbon complexes with HCl and $AlBr_3$ -hydrocarbon complexes with HBr. An especially preferred isomerization catalyst of the present invention is a mixture of boron trifluoride and hydrofluoric acid under sufficient pressure to maintain the desired concentration of BF_3 in the liquid catalyst. Although it is preferred to use the same catalytic agents throughout the present process, the present invention also contemplates that two different catalysts may sometimes be employed in separate stages.

Relatively lower catalyst activity in the first stage as compared to the catalyst activity in the subsequent stage is determined at the same conditions. Thus, when relative catalyst activities are referred to, it is meant that the activities are to be compared at the same temperature, etc. According to the present invention, catalyst activity is controlled by the proportions of the ingredients in the catalyst mixture, most suitably by the concentration of promoter or more active ingredient. For example, in using aluminum halide-hydrocarbon complexes, the catalyst activity may be increased by increasing the ratio of aluminum halide to hydrocarbon in the complex or the addition of hydrogen halide, or both; in using mixtures of boron trifluoride and hydrogen fluoride, the catalyst activity may be increased by increasing the proportion of boron trifluoride in the liquid mixture; or with aluminum chloride-hydrogen chloride mixtures, the amount of hydrogen chloride promoter may be increased to obtain greater catalyst activity.

The ratio of catalyst mixture to reactants depends at least in part upon the nature of the catalyst and reactants and upon the amount of relatively inert low-boiling isoparaffins present in the first isomerization stage and of n-paraffins present in the second isomerization stage. A large enough amount of catalyst in suitable form, either liquid or solid, is employed to yield sufficient active catalyst surface to obtain the desired isomerization in a relatively short time. A constant renewal of the active catalyst surface available to the reactants is most desirable in preventing side reactions. With the liquid type catalysts, which are preferred, the catalyst may form 5%-95% of the total liquid mixture, including the reactants, diluents, etc. When using the preferred amounts and proportions of hydrocarbons, i. e., around the middle of the ranges given, the ratio of catalyst mixture to n-paraffin to be isomerized may be from 0.2 to 2.0 by volume

and preferably is in the vicinity of 0.5, especially with HF, BF_3 mixtures.

It is especially preferable to recycle side reaction products, or like materials from extraneous sources, to each of the isomerization stages, most desirably along with recycled, low-boiling isoparaffins to the first stage and recycled normal paraffins to the subsequent stage or stages. The recycle of side reaction products in the second isomerization stage is particularly important for best results.

It is a feature of the present process that a one-pass operation in each isomerization stage, particularly the first stage, gives higher ultimate yields of the desired isoparaffins of larger number of side chains without excessive degradation. However, incidental amounts of the desired end product in each isomerization stage may be recycled thereto without appreciable change in over-all product yield.

Ordinarily, only two isomerization stages are necessary; however, where isomers of three or more side chains are being produced from normal paraffins, e. g., triptane from normal heptane, the isomerization treatment subsequent to the first stage conversion to isoparaffins mainly of one side chain may be carried out in more than one stage. In most instances, a two-stage isomerization is preferable, wherein an n-paraffin is isomerized in a first stage mainly to singly-branched paraffins, e. g., n-heptane to methylhexanes, and the first stage product, e. g., methylhexanes, or a mixture of methylhexanes and dimethylpentanes, is isomerized in a second stage all the way to the desired end product, e. g., to triptane.

In one specific embodiment, a normal paraffin of preferably seven or eight carbon atoms, such as normal heptane, is isomerized to isoparaffins predominantly having only one side chain in a first stage by thorough contact with a catalyst mixture of relatively low activity for a short period of time in the presence of a low-boiling isoparaffin, and preferably at a relatively high temperature (as compared to the second stage).

Thus, normal heptane is isomerized mainly to methylhexanes in a first stage in admixture with a low-boiling isoparaffin, such as isobutane, in a ratio of about 2-4 parts of isobutane (including that recycled) to 1 part of n-heptane. In addition, the material being charged to the first stage isomerization usually contains small amounts of side reaction products, including propane, butane, pentane, etc., which may be recycled together with catalyst and/or promoter. Part of the charge includes unreacted n-heptane and may also include relatively small amounts of methylhexanes.

The catalyst in the first stage is preferably a liquid HF, BF_3 mixture, containing about three to fifteen percent, preferably for n-heptane isomerization about eight to twelve percent by weight, BF_3 , and the remainder HF. Generally, a lesser proportion of BF_3 is used for the higher n-paraffins than for the lower n-paraffins. The ratio of catalyst to n-paraffin reactant on a volume basis in the isomerization zone may be 0.2 to 2.0 more or less and is preferably about 0.5. The feed material, including the normal paraffin to be isomerized, is thoroughly contacted with this catalyst mixture for not longer than about thirty minutes, and preferably from ten to twenty minutes at the isomerization temperature. Thorough agitation to obtain efficient contact between the catalyst and hydrocarbon feed ma-

terial is particularly important in order to permit shortest contact times, whereby the desired isomerization is attained with a minimum of degradation into side reaction products. Less preferably, longer contact times may sometimes be tolerated when only a coarse dispersion of catalyst throughout the hydrocarbon feed material is achieved. Especially favorable results are obtained when the first stage isomerization is carried out at a relatively high temperature (as compared to the subsequent isomerization) of 75° F. to 150° F., most desirably 90° F. to 125° F. Sufficient pressure is employed to maintain the desired concentration of BF_3 in the liquid catalyst.

The yields or conversions to the desired isomer in the first stage will depend upon the isomerizing conditions, the amount of recycled materials, etc., as well as the nature of the n-paraffin being treated. Usually above about 35% of the n-paraffin charged will be converted to the isomer having only one side chain.

The resultant first stage isomerization product may be separated into unreacted n-paraffin, e. g., n-heptane, and an isoparaffin concentrate of, or a fraction predominating in, isomers of only one side chain, e. g., methylhexanes. Also, the small amount of side reaction products and residual catalyst may be separated for disposal, or recycled in whole or preferably in part. The isoparaffin concentrate generally contains at least 65%, and preferably more than 80%, of isoparaffins. Usually, a concentrate of substantially pure (i. e., above 90% concentration by volume) isoparaffins is obtained, either in a primary separation, or, if necessary, in a secondary operation. The isoparaffins in the concentrate are mostly (i. e., 70% or 75% or more) singly-branched isomers. For example, under the preferred isomerization conditions with n-heptane as starting material, the first stage isoheptane concentrate or fraction generally contains at least 80% to 90% or more of methylhexanes. It is most advantageous to minimize the amount of unreacted n-paraffin in the isoparaffin concentrate, and it is preferable to recycle some singly-branched isoparaffin along with the unreacted n-paraffin rather than use as feed material to the second isomerization stage an isoparaffin concentrate containing appreciable amounts of the unreacted n-paraffin.

The separation of the isoparaffin concentrate from the first step reaction product mixture may be carried out in any suitable manner, such as by fractional distillation, solvent extraction, flash distillation, azeotropic distillation, extractive distillation, etc., or combinations thereof, in suitable apparatus, such as one or more packed or plate columns, or the like.

The concentrate or fraction of isomers predominantly of one side chain, e. g., methylhexanes, is subjected in the second isomerization step to the action of an isomerization catalyst mixture of increased activity, e. g., a liquid HF, BF_3 catalyst mixture containing a greater amount of BF_3 than in the first stage. Thus, the preferred BF_3 , HF mixture in the second isomerization reactor contains 5% to 25% BF_3 , preferably for heptane isomerization 13% to 19% BF_3 , under sufficient pressure to maintain the catalyst substantially in liquid form. On a volume basis the ratio of catalyst to isoparaffin reactant may be 0.2 to 2.0 more or less, and is preferably about 1.0.

In the second isomerization stage, it is especially important that the isoparaffin feed mate-

rial be subjected to the isomerization conditions in the presence of a substantial amount of an n-paraffin, preferably a low-boiling n-paraffin, in liquid form, and especially propane, since without it extensive degradation and the formation of unwanted products occurs. The isoparaffin feed material obtained from the first stage isomerization is preferably combined with recycled unreacted isoparaffins and intermediate isoparaffins (e. g., dimethylpentanes in heptane isomerization) produced in the second isomerization stage. Also, especially advantageous results are obtained when at least part of the side reaction products as may be separated from the desired end product are recycled or added to the feed material to the second isomerization stage. Thus, in treating heptanes, it is most desirable to recycle the side reaction products, such as isobutane, pentanes, and hexanes, to a second isomerization stage. Further, if desired, n-paraffins, e. g., low-boiling normal paraffins, such as normal butane or propane, produced as side products in the first isomerization stage may be introduced as part of the added n-paraffin in the second isomerization stage. Preferably, the ratio of n-paraffins and recycled side products to paraffins being isomerized is about 2-20 to 1; the amount of n-paraffin, such as propane, is ordinarily in considerably greater proportion than the recycled side products. Thus, for example, in a heptane isomerization using propane, a preferred feed mixture to the second isomerization stage comprises about 1 volume of isooctanes, about 8 volumes of propane, and about 1 volume of other recycled materials, including side reaction products, such as butanes, pentanes, and hexanes.

The temperature in the second isomerization step is preferably relatively low, such as below 75° F. usually between 25° F. and 60° F. or lower. Generally, the temperature is maintained so that only the isoparaffins, e. g., methylhexanes and dimethylpentanes, are isomerized without substantial effect on the relatively inert n-paraffins, such as isomerization of butane, etc.

Although the contact time in the second step is not as critical as in the first isomerization step, a relatively short contact time of about fifteen to thirty minutes or more with vigorous agitation may be employed, the longer times being used for the lower temperatures of isomerization or less efficient mixing.

Depending upon the nature of the singly branched isomers and the highly branched chain isoparaffins desired and the conditions employed, the conversion per pass to the desired product will range upwards from 15% by volume or more. Under the more preferred conditions in the second isomerization stage, ultimate conversions above about 50% will be obtained along with the production of other valuable gasoline components.

As in the first isomerization stage, the reaction products may be separated into the desired products by any suitable means, such as distillation, fractional crystallization, extraction or distillation with selective solvents, etc., or combinations thereof. Thus, for example, in the production of triptane from normal heptane, a concentrate of triptane may be obtained by fractional distillation, and the triptane separated from this concentrate by solvent distillation, i. e., extractive distillation, with a selective solvent, such as dialkylphthalates, e. g., diethylphthalate, nitro-aromatics, e. g., nitrobenzene, nitrotoluene,

etc., aromatic amines, e. g., aniline, etc., ketones, anhydrides, and the like.

It is apparent that the process of the present invention and any step thereof can be carried out either continuously or batchwise, or combinations of batchwise and continuous treatment may be used. In the isomerization stages any suitable apparatus providing thorough contact between the catalyst mixture and the various ingredients of the feed material, including recycled products and other added material, may be employed. For example, combinations of mechanically driven agitators, such as turbo mixers with settlers, used either singly or in series or parallel, packed column adapted for concurrent or countercurrent flow, coil reactors, or the like, may be used. Since it is particularly important in the present process to attain thorough contact between the catalyst and hydrocarbon mixture, it is preferred to use contacting devices, such as turbo mixers or other relatively high speed agitator and baffle arrangements, wherein the catalyst is quickly and finely dispersed throughout the hydrocarbon mixture. The material forming the isomerization reactor, or reactors, and other apparatus, especially that which is in contact with the HF, BF₃ catalyst, is ordinarily substantially inert, such as Monel, nickel, Hastalloy, etc., so that no reaction of HF and/or BF₃ takes place with the apparatus material to form substances inhibiting the isomerization reaction or to form excessive amounts of contaminants. Many suitable types of apparatus can be constructed readily by one skilled in the art, but the invention will now be described in reference to an illustrative preferred process flow shown schematically in the drawing, wherein for the sake of simplicity and clarity there have been omitted certain details, such as pumps, valves, pressuring means, coolers, heat exchangers, reflux systems, etc.

Referring to the figure showing one preferred embodiment of a continuous flow process of the present invention, normal heptane and isobutane in a 1:3 ratio together with recycled material mentioned hereinbelow are introduced through lines 11 and 12 respectively into a first stage isomerization reactor 10, which may be a turbo mixer operated to achieve a fine dispersion of catalyst throughout the hydrocarbon mixture. The temperature within the isomerization reactor 10 is maintained at about 100° F. An HF, BF₃ catalyst mixture is also introduced into the isomerization reactor 10 through line 13 at a rate sufficient to give a liquid catalyst of about 8 to 12% BF₃ by weight and a liquid catalyst to normal heptane ratio of about 0.5 on a volume basis. The total amount of BF₃ introduced into the reactor will depend upon the equilibrium pressure of BF₃ at the temperature employed, the ratio of liquid catalyst to hydrocarbon and the gas space above the liquid mixture. Thus, sufficient pressure, such as 100-400 lbs./sq. in. of BF₃ is used to maintain the desired concentration of BF₃ in the liquid catalyst. For example, a total of about 25% BF₃ based by weight on the HF, BF₃ mixture was introduced into an isomerization reactor under about 150 lbs./sq. in. total gauge pressure and containing 1.9 liters of liquid at 100° F. and 2.9 liters of gas space at 120° F. When, as is preferred, a thorough contact between the catalyst and hydrocarbon mixture is quickly attained in the reactor 10, the rates of flow of hydrocarbons and catalyst are gauged to

give a contact time in the isomerization reactor of about fifteen minutes.

A mixture of catalyst and hydrocarbons discharges from reactor 10 through line 15 into settler 16, wherein a separation into a hydrocarbon phase and a catalyst phase takes place. Ordinarily, at least part of the catalyst phase is recirculated to the reactor 10 through lines 17 and 13. Part of the catalyst may be withdrawn through line 18 for regeneration or other disposal.

As illustrative of the first stage isomerization, a batchwise experimental run was carried out at 100° F. and 15 minutes contact time in a reactor of 4.8 liter volume and under 267 lbs./sq. in. absolute pressure, giving a BF_3 partial pressure of about 182 lbs./sq. in. absolute and about 11.7 weight percent of BF_3 in the liquid catalyst phase, as follows:

Run A

Charge to reactor, grams:

HF	213
BF_3	162
Propane	15
Isobutane	597
Normal butane	28
Normal heptane	270
C_{5+} product recovered, grams	260
2,2,3-trimethylbutane	2.9
3,3-dimethylpentane	1.3
2,3-dimethylpentane	9.1
2,4-dimethylpentane	16.2
2-methylhexane	44.2
3-methylhexane	28.0
Normal heptane	151.1
Octanes +	7.3
Heptanes lost ¹	10.0

¹ Includes losses through side reactions and mechanical losses.

The hydrocarbon phase leaving the settler 16 is a mixture of methylhexanes, dimethylpentanes (in a ratio of about 1 to 4-5 with the methylhexanes), isobutane, some unreacted normal heptane, some HF and BF_3 , and relatively small amounts of side reaction products, such as propane, butanes, pentanes, etc. This mixture passes through line 20, preferably first to a recycle rectifier 21, wherein conditions are maintained to remove everything boiling up to but not including heptanes. The mixture of HF, BF_3 , isobutane, and lower-boiling side reaction products may be recycled in whole or in part through lines 22 and 12 to the first stage isomerization reactor 10. In some instances, it is desirable to pass the whole or part of this low-boiling mixture through line 24, to a suitable vessel or column, called for convenience, first stage depropanizer 25. Therein materials boiling below isobutane and thus including HF, BF_3 , and propane are separated from isobutane which is recycled to the reactor 10 through lines 26, 22 and 12. The lower boiling materials, i. e., HF, BF_3 , and propane, leave depropanizer 25 through line 27 and may be discarded or disposed of, such as for example as mentioned hereinbelow.

The heptanes, including methylhexanes, dimethylpentanes and unreacted normal heptane which are substantially free of lower boiling materials, pass from recycle rectifier 21 through line 30 to a suitable separator, such as heptane still 31. Therein a separation between unreacted normal heptane and isoheptanes is effected, the normal heptane recycling at least in part through line 32 to first stage isomerization reactor 10.

Preferably, the heptane still 31 is a fractional distillation column of a sufficient number of theoretical plates for an efficient separation between normal heptane and isoheptanes. The present process is most effective when the overhead from the separation in heptane still 31 contains little or no n-heptane and thus the bottoms withdrawn for recirculation may contain some methylhexanes. Although the heptane still 31 is shown as a single column or unit, two or more columns may be used in a conventional multi-stage fractionation with intermediate recycle streams to obtain an isoheptane concentrate of at least 60% and preferably above 90% of isoheptanes.

The first stage isoheptanes comprising mainly methylhexanes and leaving still 31 through line 35, are introduced into the second isomerization stage reactor 40 through line 41. Propane or other, preferably low-boiling, normal paraffin in about 8:1 ratio with the isoheptane is likewise introduced through lines 42 and 41 into isomerization reactor 40. Preferably recycle streams including propane, some catalyst, dimethylpentanes, unreacted methylhexanes, and side reaction products (i. e., butanes, pentanes, and hexanes) are added via lines 44 and 45 to flow into reactor 40 as described hereinbelow. Sufficient side reaction products may be recycled to give a ratio of them to isoheptanes of about 1:1. Part of the propane introduced into second stage isomerization reactor 40 may be supplied from the reaction products from the first stage isomerization; thus, at least part of the propane together with HF and BF_3 separated in first stage depropanizer 25 may be directed into the second stage isomerization reactor 40, and for this purpose line 48 from depropanizer overhead line 27 connects with propane line 42.

Catalyst is introduced into second stage isomerization reactor through line 50 and may comprise either in whole or in part either fresh catalyst from line 51 or recycled catalyst from line 52. The preferred HF, BF_3 catalyst mixture in reactor 40 contains about 13 to 19% by weight, and sufficient catalyst is introduced to maintain a catalyst to isoheptane ratio of about 1.0 on a volume basis. The pressure in the isomerization reactor 40 is at least sufficient to keep the desired concentration of BF_3 in the liquid catalyst and the propane mainly in liquid form. With thorough agitation the contact time between the catalyst and hydrocarbons in the isomerization reactor 40 is about fifteen to twenty minutes, and the temperature is maintained at about 50° F.

The catalyst and hydrocarbon mixture leaving the second stage isomerization reactor 40 passes through line 55 to settler 56, wherein a separation into a hydrocarbon phase and a catalyst phase takes place. The catalyst phase may be in whole or in part either recycled through line 52 to the reactor 40 or passed through disposal line 57 for rejection or suitable regeneration.

As illustrative of the second stage isomerization, batchwise experimental runs at 50° F. and 15 minutes contact time were carried out in a reactor of 4.8 liters volume. In Run B, the total pressure was 245 lbs./sq. in. absolute, giving a BF_3 partial pressure of about 158 lbs./sq. in. and about 17.0 weight percent of BF_3 in the liquid catalyst phase. In Run C, the total pressure was 225 lbs./sq. in. absolute, giving a BF_3 partial pressure of about 163 lbs./sq. in. and about 17.5%

BF₃ in the liquid catalyst phase. The charge and product composition was as follows:

Run No.	B	C ¹

¹ The total pressure was 210 lbs./sq. in. gauge, giving a BF₃ partial pressure of 163 lbs./sq. in.

² Both losses through side reactions and mechanical losses are included.

The hydrocarbon phase contains triptane, dimethylpentanes, unreacted methylhexanes, some catalyst, and a small amount of side reaction products, such as butanes, pentanes, and hexanes. This hydrocarbon phase passes through line 60 to a suitable separator, such as second stage depropanizer 61, whereby propane and lower boiling material including HF and BF₃, are removed for recycle through lines 62 and 44 to second stage reactor 49. Material boiling higher than propane passes from depropanizer 61 through line 65 to a further separator, such as a dehexanizer 66, for separation into two fractions: one containing materials boiling below heptanes, such as the small amounts of side reaction products including butanes, pentanes, and hexanes, and a second fraction containing the heptanes and small amounts of higher boiling materials. The lower boiling fraction discharges from dehexanizer 66 through line 67, from whence it may be recycled to the second stage reactor 49 through lines 44 and 41 or to other disposal through line 68 or both. In general, although side reaction products, such as butanes, pentanes, and hexanes, together with the mixture of recovered propane, HF and BF₃ may be recycled to the second stage reactor 49, a separation of the HF, BF₃ mixture from the hydrocarbons may be effected in any suitable manner, whereby all or part of each of the separated portions may be recycled or disposed of in other ways. Thus, part of the HF, BF₃ mixture may pass to a suitable catalyst regeneration, and the hydrocarbons other than that required for recycle may be used for blending in gasolines.

The higher boiling heptane fraction leaving dehexanizer 66 passes through line 70 into isohexane fractionator 11. Therein, the heptane fraction is separated into a lower boiling triptane concentrate containing 2,4-dimethylpentane and a higher boiling fraction containing 2,3-dimethylpentane and methylhexanes. The latter fraction or bottoms may be withdrawn through line 72 and recycled to second stage isomerization reactor 49 through lines 45 and 41. If desired, all, or preferably only part, of the bottoms may be further separated by passing through line 73 to rerun still 89, wherein small

amounts of heavier material boiling above heptanes, such as octanes, etc., may be removed through line 81, the heptanes passing through line 82 to recycle line 45. The fractionator 11 is preferably a distillation column or columns, either packed, tray, or bubble-cap type, of a sufficient number of theoretical plates to effect a separation between the two desired isohexane fractions. Thus, a top temperature equivalent to about 1780 F. to 185° F. at atmospheric pressure may be maintained. The almost negligible amount of 2,2-dimethylpentane and 3,3-dimethylpentane formed will be found in the triptane concentrate and the heptane fractionator bottoms, respectively. It is one of the advantages of the present invention as preferably applied to triptane production from n-heptane that the use of an n-paraffin, particularly propane, in the second isomerization stage causes little or no formation of 2,2-dimethylpentane and 3,3-dimethylpentane, thereby permitting a better separation between triptane and 2,4-dimethylpentane on one hand and the remaining isohexanes on the other hand; however, when isobutane instead of propane is used as the principal diluent in the second isomerization stage, appreciable amounts of these neo-carbon atom dimethylpentanes are formed partly at the expense of triptane production.

The triptane concentrate leaving heptane fractionator 11 through line 85 contains about 40% or more triptane and the remainder almost entirely 2,4-dimethylpentane. Although this triptane concentrate has a fairly high octane number and may thus be used as such for aviation fuel, it is more preferable to separate further to get at least 80%, and most desirably substantially pure (i. e., above 90%), triptane. Due to the closeness in boiling points of triptane and 2,4-dimethylpentane fractional distillation cannot ordinarily be used. A suitable method of separation involves the use of selective solvents. Thus, the triptane concentrate may be passed through line 86 to an extractive distillation system. For example, in the schematic extractive distillation system shown, triptane concentrate is introduced into the middle portion of a suitable column 96 while a selective solvent, such as diethylphthalate, is introduced through line 91 into the upper portion. Substantially all or at least a principal amount of the 2,4-dimethylpentane together with any 2,2-dimethylpentane present is taken overhead through line 92 and recycled through lines 45 and 41 to the second stage isomerization reactor 49. A mixture of triptane and solvent along with small amounts of 2,4-dimethylpentane is withdrawn and passed through line 93 to a suitable separator or fractionator 94, wherein triptane is removed from the solvent and passes out through line 95. The remaining solvent is recycled through line 91 to distillation column 90.

The triptane thus obtained may be of about 80% concentration but is usually in the vicinity of 90% or above. If further purification is required, it is usually suitable to employ fractional crystallization, whereby triptane may be readily crystallized from the mixture.

By means of the above-described preferred process flow of the present invention, high yields of triptane can be obtained from n-heptane by isomerization. The ultimate over-all conversion of n-heptane to triptane is in the vicinity of 50% or higher, the remainder consisting mainly of valuable gasoline components. Thus, for the

first time triptane is produced in good yields by isomerization.

As illustrative of the above-described process, the following example is given:

First stage isomerization

Conditions:

Temperature=100° F.

Contact time=15 min.

Catalyst (liquid)=10% BF_3 , 90% HF

Ratio of catalyst to total hydrocarbons=14:36
by volume

Charge:

1000 B./D. (barrels per day) fresh n-heptane

1780 B./D. n-heptane recycled

8350 B./D. isobutane recycled

Product:

1000 B./D. isoheptanes

1780 unreacted n-heptane

8350 B./D. isobutane

0.75 B./D. heavy oils from acid phase

Second stage isomerization

Conditions:

Temperature=50° F.

Contact time=15 min.

Catalyst (liquid)=19% BF_3 , 81% HF

Ratio catalyst to total hydrocarbons=14:86
by volume

Charge:

1000 B./D. isoheptanes from first stage.

2440 B./D. isoheptanes recycled

18400 B./D. propane recycled

1225 B./D. isobutane

980 B./D. pentanes

980 B./D. hexanes

Product:

18400 B./D. propane

2440 B./D. isoheptane (other than triptane)

500 B./D. triptane

1381 B./D. isobutane

1046 B./D. pentanes

1055 B./D. hexanes

29 B./D. heavy oils from acid phase

192 B./D. octanes and heavier

Although the above described process flow and example represent illustrations of a preferred embodiment of the present invention, it will be readily appreciated that many modifications and changes may be made without departing from the spirit and scope of the present invention as defined by the claims hereinbelow. Thus, while ordinarily two separate reactors will be used for the isomerization stages, these may in some circumstances be incorporated into one unit, tower or contactor with intermediate separations and recycle streams.

Further, instead of using the preferred propane as the principal diluent in the second isomerization stage, other n-paraffins, preferably low-boiling, may be employed, in which case the second stage depropanizer 61 will not ordinarily be operated at least as such. In the event n-heptane is employed in the second isomerization stage of a triptane process, the second stage depropanizer 61 may be omitted, and the hydrocarbon phase from settler 56 passed directly into dehexanizer 66, in which case it is preferable to separate by suitable means the dehexanizer overhead material into HF, BF_3 mixture and hydrocarbons, for example, in order to obtain more controlled recycle operation.

Instead of substantially pure n-paraffins as starting materials for the present process, substantially pure, or fractions containing singly

branched-chain higher paraffins, such as methylhexanes, methylheptanes, methyloctanes, methylnonanes, etc. may be employed. Likewise, in some cases mixtures of n- and iso-paraffins may be used to advantage, in which event the mixtures are preferably introduced into the system in such manner that a fractional separation takes place before the feed enters the isomerization zones. For example, when a heptane fraction containing some isoheptanes, such as about 10% to 30% or more of methylhexanes, constitutes the fresh feed to the first isomerization stage instead of substantially pure n-heptane in the above process, it is preferable to introduce such heptane fraction into the heptane still 31 rather than directly into isomerization reactor 10.

In the above described triptane production process, it may sometimes be advisable instead of separating the triptane concentrate by extractive distillation, to subject this mixture of triptane and 2,4-dimethylpentane to a selective isomerization process, whereby the latter is isomerized to 2,3-dimethylpentane and methylhexanes which are relatively easily separated by fractional distillation from triptane. For example, 1 part of a triptane concentrate is vigorously agitated for a short time, such as about 15 minutes, at approximately 50° F. with about 0.2-2.0 parts by weight of an isomerization catalyst consisting of 0.1% to 5%, preferably about 1%, by weight of BF_3 in the liquid catalyst and the remainder HF. The hydrocarbon phase separated from the liquid catalyst is fractionally distilled to remove the 2,3-dimethylpentane and methylhexane, which may be recycled to the second stage isomerization. The low-boiling triptane concentrate thereby obtained contains less than half as much 2,4-dimethylpentane. Thus, for example, a triptane concentrate containing about 20% 2,4-dimethylpentane when so treated yields a new triptane fraction containing less than about 10% 2,4-dimethylpentane.

Although the present process is especially and preferably applicable to n-heptane isomerization, other n-paraffins, such as hexane, octane and nonanes, may be advantageously treated according to the present invention. When the higher n-paraffins are isomerized, it is usually more desirable to use somewhat lower catalyst activities or lower temperatures, or both. However, it is an essential feature that the first stage isomerization be carried out in the presence of a substantial amount of an isoparaffin and preferably an isomerization catalyst of relatively low activity and the subsequent isomerization of the first stage isomers be carried out in the presence of a substantial amount of a liquid n-paraffin and preferably an isomerization catalyst of high activity (said catalyst activities being compared at the same conditions).

While the especially preferred catalyst consists of HF and BF_3 and generally the present process is most effectively carried out therewith, other catalysts as mentioned hereinabove may sometimes be used to advantage. As illustrative thereof, the conditions of isomerization may be in the vicinity of those given in the following examples:

Example 1.—An aluminum chloride-hydrocarbon complex containing about 65% to 75% by weight AlCl_3 and 35% to 25% hydrocarbon, such as is formed in butane isomerization, is employed in the present stepwise isomerization process, wherein the general conditions in the stages may be as follows:

In the first stage, with a temperature of 75° F. to 125° F. and a contact time of five to forty-five minutes, the aluminum chloride-hydrocarbon complex contains about 0.5 to 15 mol percent of hydrogen chloride and the remainder $AlCl_3$ exclusive of the hydrocarbon. The activation of the aluminum chloride-hydrocarbon complex may be obtained, for example, by a partial pressure of hydrogen chloride of one to two hundred pounds per square inch.

In the second stage, the temperature of 40° F. to 75° F. and a contact time of five to forty-five minutes may be suitable. A mol ratio of HCl to $AlCl_3$ of 0.5/99.5 to 20/80 may be obtained with an HCl partial pressure of about fifteen to three hundred pounds per square inch.

Other conditions, such as of ratios of catalyst and diluents to the hydrocarbon being isomerized, etc., will be generally of the order of the ranges given hereinabove in connection with the preferred HF , BF_3 liquid catalyst mixture.

Example 2.—An aluminum bromide-hydrocarbon complex may be employed under the general illustrative conditions set out above for aluminum chloride-hydrocarbon complex.

As hereinbefore mentioned, the catalyst activities and temperature in one or both of the isomerization stages may be varied from the ranges given for the preferred general embodiment, while retaining at least part of the advantages of the present invention.

Thus, in some instances, where a greater production of side reaction products can be tolerated, i. e., where the side reaction products can be economically or readily utilized, such as for blending in aviation fuel or for other purposes, either or both higher catalyst activities and higher temperatures may be employed in one or both isomerization stages. For example, the activity of the catalyst in the first stage may even approach or exceed that of the catalyst in the second stage, and/or the temperature in the second stage may be raised to about that of the first stage or higher. Generally, the catalyst activities will not exceed those indicated hereinabove for that of the second stage. Ordinarily, under the above criterion the catalyst activity in the first stage will not be as critical as in the second stage and thus can be raised with a consequent increase in conversion. It is to be understood that such modifications will be made with due correlation with the nature of the hydrocarbons being treated, nature of the catalyst, ratios between reactants, catalyst, diluents, etc., contact times, etc. For example, when either the temperature of catalyst activity is raised, especially in the second stage, the lower boiling n-paraffin diluents are used in order to avoid excessive side reactions producing undesirable materials. In any event, it remains an essential feature to carry out the first stage isomerization in the presence of a substantial excess of a low-boiling isoparaffin and the subsequent isomerization of the first stage product or fraction thereof in the presence of a substantial excess of an n-paraffin, especially propane, in liquid form.

I claim:

1. A process for isomerizing n-heptane which comprises intimately contacting one volume of n-heptane and 2 to 4 volumes of iso-butane with

at least 0.2 volume of a liquid isomerization catalyst consisting of HF and 8-12% by weight of BF_3 at a temperature in the range of 90-125° F. for a period not exceeding 30 minutes, separating from the isomerization product an iso-heptane concentrate comprised of methyl hexanes and dimethyl pentanes, intimately contacting one volume of said iso-heptane concentrate with at least 0.2 volume of a liquid isomerization catalyst consisting of HF and containing from 13-19% by weight of BF_3 at a temperature of 25-60° F. for a period not exceeding 30 minutes and in the presence of 6 to 12 volumes of liquid propane whereby the formation of 2,2- and 3,3-dimethyl pentanes is substantially reduced, and producing an isomerization product containing substantial proportions of triptane.

2. A process for isomerizing n-heptane which comprises intimately contacting one volume of n-heptane and 2 to 4 volumes of iso-butane with at least 0.2 volume of a liquid isomerization catalyst consisting of HF and 8-12% by weight of BF_3 at a temperature in the range of 90-125° F. for a period not exceeding 30 minutes, separating from the isomerization product an iso-heptane concentrate comprised of methyl hexanes and dimethyl pentanes, intimately contacting one volume of said iso-heptane concentrate with at least 0.2 volume of a liquid isomerization catalyst consisting of HF and containing from 13-19% by weight of BF_3 at a temperature of 25-60° F. for a period not exceeding 30 minutes and in the presence of 6 to 12 volumes of liquid propane whereby the formation of 2,2- and 3,3-dimethyl pentane is substantially reduced, and producing an isomerization product containing predominant amounts of 2,2,3-trimethyl butane and 2,4-dimethyl pentane, separating the major portion of said 2,4-dimethyl pentane from said trimethyl butane fraction and recycling said separated 2,4-dimethyl pentane to the second isomerization stage.
